UNITED STATES PATENT OFFICE

HARRY E. DYKEMAN, OF CHICAGO, ILLINOIS, ASSIGNOR TO UNION SPECIAL MACHINE COMPANY, OF CHICAGO, ILLINOIS, A CORPORATION OF ILLINOIS

SEWING MACHINE FOR INSERTING ELASTIC BANDS IN STITCHED ARTICLES

Application filed February 10, 1930. Serial No. 427,210.

The invention relates to new and useful improvements in a sewing machine, and more particularly to a sewing machine for inserting an endless elastic band in a stitched article.

An object of the invention is to provide a sewing machine having a stitch forming mechanism and a hem folder for inturning the edge of a fabric section with means for guiding an endless elastic tape into the hem pocket which includes a guiding roller located in front of the stitching mechanism and so disposed as to prevent any lateral shifting or creeping of the elastic tape in the hem folder.

A further object of the invention is to provide a machine of the above type with a guiding roller located in rear of the stitching mechanism, which guiding roller is provided with a shoulder and a tapered face which insures the feeding of the tape after it is stitched to the article in a fixed line away from the stitching mechanism.

A further object of the invention is to provide a machine of the above type wherein the hem folder has an inner member over which the fabric is folded adapted to be withdrawn from the hem fold for permitting the completion of the stitching of the endless elastic tape to a circular article.

A further object of the invention is to provide a machine of the above type wherein the guiding roller in front of the stitching mechanism is shiftably mounted on a horizontal rod toward and from the stitching mechanism and wherein the guiding roller in rear of the stitching mechanism is shiftably mounted on a horizontal rod so that the position of the guiding rollers may be changed for varying the tension on the elastic tape or for circular articles of different sizes without interfering with the feed of the elastic tape in a straight line into and through the hemmer and to the stitching mechanism.

These and other objects will in part be ob-

vious and will in part be hereinafter more fully disclosed.

In the drawings which show by way of illustration one embodiment of the invention:

Figure 1 is a view of a portion of a sewing machine having the improvements applied thereto, the view being taken from the end of the work arm.

Figure 2 is a plan view of the work arm and the parts carried thereby.

Figure 3 is a view from the front of the machine.

Figure 4 is a sectional view on the line 4-4 of Figure 1.

Figure 5 is a sectional view through the folder.

Figure 6 is a diagrammatic view showing a hem pocket with elastic tape stitched therein.

The invention is shown applied to a sewing machine which includes a supporting standard 1 carrying a work support 2, which, as shown, is cylindrical. Also mounted on the standard 1 is an overhanging arm 3 carrying a needle head 4 in which a needle bar 5 reciprocates. The needle bar is herein shown as provided with a needle 6. The material is held on the work support by a presser foot 7 and is fed across the work support by a feeding mechanism of the usual character located within the cylindrical work support. Located in front of the work support is a hem folder including an outer folding member 8 and an inner folding member 9.

This outer folding member 8 is adjustably fixed to a plate 10 by screws 11, 11. The plate 10 in turn is mounted on a bracket 12 secured to the cylindrical bed plate. The inner folding member 9 is attached to a rod 13 which is shifted by means of a spring 14 so as to hold said inner folding member within the outer folding member. This is the normal position of the parts of the folder for forming an infolded hem pocket in which the edge

portion of the fabric is turned downwardly and thence inwardly forming the hem pocket.

The rod 13 is moved to the left as viewed in Fig. 3 by means of a rock lever 15 mounted on the standard 1 and connected to a suitable knee shift or treadle. A spring 16 connected to the rock lever and the standard normally holds the rock lever against a stop on the standard. Located in rear of the stitching mechanism is a horizontal supporting rod 17. This rod is secured to a bracket 18 which in turn is secured to the bracket 12. The rod 17 is provided with a recess 19 in one face thereof and a slot 20 in the other face thereof which extends through to the recess 19.

Mounted for shiftable movement in said recess 19 is a block 21. The block 21 is secured in shifted positions by hand screws 22, 22 which pass through the slot 20 and are threaded into the block. These hand screws are provided with shoulders which overlie the edges of the slot. Thus it is that the block is fixed in set positions.

Mounted on this block is a depending member 23. On this depending member is a vertically shiftable block 24. Carried by the vertically shiftable block 24 is a roller support 25. The roller support 25 is connected to the block so that it may be adjusted horizontally while the block is adjusted vertically. Through these connections the support for the guide roller may be adjusted toward and from the stitching mechanism. It may be adjusted horizontally or laterally of the line of feed and it may be adjusted vertically.

Mounted on this roller support 25 is a guide roller 26. This guide roller 26 is mounted for free rotation on the support and is provided with a tapered portion 27 and a cylindrical portion 28. Between the tapered portion and the cylindrical portion is a shoulder 29. This roller is so positioned that the elastic tape when passing over the guide roller will lie close to the shoulder and the shoulder together with the tapered portion will prevent the elastic tape from creeping laterally on the guiding roller.

Attached to the plate 10 carrying the hem folder parts is a horizontal rod 30. Said rod is clamped to the plate by screws 31, 31 which permit the rod to be shifted laterally of the line of feed in a horizontal plane. This rod is provided with a recess 32 extending along one face thereof and a slot 33 in the other face which extends through into the recess.

Mounted in this recess 32 is a shiftable block 34. Said block is held in shifted positions by hand screws 35, 35 which pass through the slot and are threaded into the block. These hand screws have shoulders overlying the side edges of the slot. Fixed to the block 34 is a vertical depending member 36. The member 36 is secured to the block by screws 37, 37. Mounted in the depending

member for vertical adjustment therein is a block 38. Said block is secured in adjusted positions by a screw 39. Attached to the block 38 is the elastic strip support 40. Said support is attached to the block by a screw 41 70 which permits the elastic strip support to be shifted laterally. Through these connections the elastic strip support may be raised and lowered, shifted toward and from the stitching mechanism, and shifted laterally of the 75 line of feed both through the adjustable connection between the support and the block 38 and also the adjustable connection between the rod and the block carrying the hem folder parts. The guide for the elastic strip which is carried by the support 40 includes a roller 42 mounted on an arm 43. This arm 43 is a part of the support 40. The arm 43 extends upwardly at 43a, thence laterally at 43b, and thence downwardly at 43c, and it is on this depending end 43c of the arm that the guide roller 42 is mounted. The upwardly extending portion 43a of the arm is provided with spaced projecting portions 44, 44, thus forming a guiding recess for the tape. 80

The roller is provided with flanges 45, 45, and the tape passes across the roller between these flanges. The roller is tapered slightly outward in a downward direction. Adjacent the roller and between said roller and the hemmer is a guiding plate 46. This guiding plate 46 is rigidly attached to the portion 43 of the arm and the portion of the arm at the other side of the guiding roller 42. The plate has spaced projecting portions 47, 47. 90

Mounted on the cylindrical work support is a circular guiding shield 48 (see Fig. 2). The elastic tape is guided through the hem folder, underneath the presser foot, over the guide roller 26 at the rear of the presser foot, then underneath the shield or guide 48 and thence across the roller 42, after which it passes over the plate 46 and into the hemmer. 105

The elastic tape is an endless member. In the drawings the elastic tape is shown as stitched in a hem pocket and free from the line of stitching. The fabric is indicated at F; the infolded portion at f. The elastic tape is indicated at E, and the line of stitching at S. This elastic tape as it leads into the hem folder passes into the pocket formed by the folding of the fabric portion and it will thus be properly located in the pocket as it is stitched. The guide roller 42 over which the tape passes to the hem folder, as noted, is mounted for rotation about an inclined axis. The tape as it passes over this roller lies in a plane which is slightly inclined to the vertical; the tape is almost vertical. The tape as it passes beneath the presser foot is, of course, horizontal and the angle of the tape gradually shifts as it leads toward the hem folder and the tape is substantially horizontal as it passes into the folder. 110

One of the advantages of this inclining 130

of the guide roller in front is to prevent any lateral creeping of the tape on the guide roller. It is essential that this elastic tape shall be fed in a predetermined fixed path 5 through the hem folder so as not to interfere with the folding of the fabric portion and so as to be properly placed in the stitched pocket. By inclining the roller there is no possible chance of the elastic tape shifting laterally 10 at the point where it leaves the guiding roller for the hem folder. Furthermore, by mounting the roller in the manner stated, a relatively small roller may be used and the guiding devices which necessarily open to a certain extent the loop end of the elastic tape 15 passing thereabout open said elastic tape substantially horizontally and this greatly aids in the guiding of a circular fabric about the guiding means.

20 Preferably, however, in the stitching of elastic tape in a pocket when the part which has been finished approaches the guide roller 42, the machine is stopped and the elastic tape is removed therefrom and held under 25 tension by the finger of the operator. As the initially stitched portion approaches the hem folder, then through the treadle the inner member of the hem folder is withdrawn and this allows the initially stitched portion to 30 pass through the outer member of the hem folder and the completing of the stitching of the article.

It will be noted that the guide rollers both in front and in rear of the stitching mechanism 35 are disposed so that the elastic tape is guided in substantially a horizontal line passing just above the plane of the work support and beneath the presser foot. When either guide roller is shifted toward or from the 40 stitching point, it is shifted horizontally and this line of movement of the elastic tape is not altered. The guide roller in front of the stitching mechanism is readily capable of vertical or lateral adjustments and may 45 be positioned so that the tape will be guided with certainty into the hem folder and positioned in the hem pocket as desired relative to the line of stitches which is to be produced. Then again, this guide roller in front of the 50 stitching mechanism may be shifted toward and from the stitching mechanism for varying the tension on the elastic strip or for articles of different sizes. The guide roller in rear of the stitching mechanism may like- 55 wise be raised and lowered and shifted laterally to aid in the positioning of the elastic strip as desired relative to the needle of the stitching mechanism. This guide roller may also be shifted toward and from the stitching 60 point for increasing the tension on the elastic strip or for articles of different sizes.

It is thought that the operation of the machine will be obvious from the description which has been given above. The elastic tape is placed in the machine about the guide

rollers and beneath the presser foot. The fabric is fed into the hem folder and as the hem pocket is formed it is formed about the elastic tape. Thus it is that a circular article may be stitched, the pocket formed therein 70 and an elastic tape enclosed within the pocket, which elastic tape is under tension when the pocket is formed.

It is obvious that minor changes in the details of description and the arrangement of the parts may be made without departing from the spirit of the invention as set forth in the appended claims.

Having fully described my invention, what I claim as new and desire to secure by Letters Patent, is:—

1. The combination of a work support, a stitching mechanism, a folder located in front of the stitch forming mechanism for inturning the edge portion of a fabric to form a hem pocket, and means for guiding an endless elastic tape through the folder and into the formed hem pocket, said means including a guide roller located in advance of the folder for guiding and directing the elastic tape into said folder, said guiding roller being mounted for rotation on an axis inclined to the plane of the work support whereby the elastic tape is directed in predetermined fixed path into the folder. 85

2. The combination of a work support, a stitching mechanism, a folder located in front of the stitch forming mechanism for inturning the edge portion of a fabric to form a hem pocket, and means for guiding an endless elastic tape through the folder and into the formed hem pocket, said means including a guide roller located in advance of the folder for guiding and directing the elastic tape into said folder, said guiding roller being mounted for rotation on an axis inclined to the plane of the work support, and devices for supporting said guiding roller whereby it may be shifted vertically, horizontally, or toward and from the stitching mechanism. 100

3. The combination of a work support, a stitching mechanism, a folder located in front of the stitch forming mechanism for inturning the edge portion of a fabric to form a hem pocket, and means for guiding an endless elastic tape through the folder and into the formed hem pocket, said means including a guide roller located in advance of the folder and rotatable about an axis inclined to the plane of the work support whereby the tape is directed in a predetermined fixed path into the folder, a guide roller located in rear of the stitching mechanism over which guiding rollers the elastic tape passes, and devices for supporting said guiding rollers whereby they may be shifted toward and from the stitching mechanism. 105

4. The combination of a work support, a stitching mechanism, a folder located in front of the stitch forming mechanism for inturn- 110

115

130

ing the edge portion of a fabric to form a hem pocket, and means for guiding an endless elastic tape through the folder and into the formed hem pocket, said means including a guide roller located in advance of the folder and rotatable about an axis inclined to the plane of the work support, a guide roller located in rear of the stitching mechanism over which guiding rollers the elastic tape passes, and devices for supporting said guiding rollers whereby they may be shifted vertically, horizontally, or toward and from the stitching mechanism.

5. The combination of a work support, a stitching mechanism, a folder located in front of the stitch forming mechanism for inturning the edge portion of a fabric to form a hem pocket, and means for guiding an endless elastic tape through the folder and into the formed hem pocket, said means including a guide roller located in advance of the folder for guiding and directing the elastic tape into said folder, said guiding roller being mounted for rotation on an axis inclined 25 to the plane of the work support, and devices for supporting said guiding roller whereby it may be shifted vertically, horizontally, or toward and from the stitching mechanism, a guide roller located in the rear 30 of the stitching mechanism, said guiding roller in rear of the stitching mechanism having a shoulder formed therein and a tapered portion at one side of said shoulder for preventing the elastic tape from creeping laterally 35 on said guiding roller.

6. The combination of a work support, a stitching mechanism, and means for guiding an endless elastic tape to the stitching mechanism, said means including a guide roller located in advance of the stitching mechanism and mounted for rotation about an axis inclined to the plane of the work support whereby the tape is directed in a predetermined fixed path into the folder, and a guide 45 roller located in rear of the stitching mechanism.

7. The combination of a work support, a stitching mechanism, and means for guiding an endless elastic tape to the stitching mechanism, said means including a guide roller located in advance of the stitching mechanism and mounted for rotation about an axis inclined to the plane of the work support whereby the tape is directed in a predetermined fixed path into the folder, a guide roller located in rear of the stitching mechanism, and devices for supporting said guiding rollers whereby they may be shifted toward and from the stitching mechanism.

8. The combination of a work support, a stitching mechanism, a folder located in front of the stitching mechanism for inturning the edge portion of a fabric to form a hem pocket, and means for guiding an endless elastic tape 65 through the folder and into a formed hem

70 pocket, said means including a guide roller located in advance of the folder and rotatable about an axis inclined to the plane of the work support, an arm for supporting said roller, said arm having spaced projecting devices forming a guide for directing the elastic tape to said roller.

9. The combination of a work support, a stitching mechanism, a folder located in front of the stitching mechanism for inturning the edge portion of a fabric to form a hem pocket, and means for guiding an endless elastic tape 75 through the folder and into a formed hem pocket, said means including a guide roller located in advance of the folder and rotatable about an axis inclined to the plane of the work support, an arm for supporting said roller, said arm having spaced projecting devices forming a guide for directing the elastic tape to said roller, said guiding roller 80 having spaced flanges and a tapered portion between said flanges for receiving and guiding the elastic tape.

10. The combination of a work support, a stitching mechanism, a folder located in front 90 of the stitching mechanism for inturning the edge portion of a fabric to form a hem pocket, and means for guiding an endless elastic tape through the folder and into a formed hem pocket, said means including a 95 guide roller located in advance of the folder and rotatable about an axis inclined to the plane of the work support, an arm for supporting said roller, said arm having spaced projecting devices forming a guide for directing the elastic tape to said roller, said guiding roller 100 having spaced flanges and a tapered portion between said flanges for receiving and guiding the elastic tape, a rod extending from said work support on which 105 said arm for the guiding roller is mounted and shiftable toward and from the stitching mechanism.

11. The combination of a work support, a stitching mechanism, a folder located in front 110 of the stitch forming mechanism for inturning the edge portion of a fabric to form a hem pocket, and means for guiding an endless elastic tape through the folder and into the formed hem pocket, said means including 115 guiding devices located in advance of the folder, a rod mounted on the work support and projecting horizontally therefrom, a block shiftable endwise of said rod and carrying a depending member, a block on said depending member and shiftable vertically thereon, and an arm shiftable horizontally on said block and carrying said guiding devices.

12. The combination of a work support, a stitching mechanism, a folder located in front 125 of the stitch forming mechanism for inturning the edge portion of a fabric to form a hem pocket, and means for guiding an endless elastic tape through the folder and into 130

the formed hem pocket, said means including a guide roller located in rear of the stitching mechanism, a horizontal rod carried by the work support projecting rearwardly therefrom, a block shiftable lengthwise of said rod, a depending member carried thereby, a block shiftable vertically on said depending member, and an arm shiftable horizontally on said last-named block and carrying said guiding roller.

13. The combination of a work support, a stitching mechanism, a folder located in front of the stitch forming mechanism for inturning the edge portion of a fabric to form a hem pocket, and means for guiding an endless elastic tape through the folder and into the formed hem pocket, said means including a guide roller located in rear of the stitching mechanism, a horizontal rod carried by the work support projecting rearwardly therefrom, a block shiftable lengthwise of said rod, a depending member carried thereby, a block shiftable vertically on said depending member, and an arm shiftable horizontally on said last-named block and carrying said guiding roller, said guiding roller having a cylindrical portion and a portion tapering toward the cylindrical portion and forming a shoulder whereby said tapered portion guides said elastic tape in a predetermined path.

14. The combination of a work support, a stitching mechanism, a folder located in front of the stitch forming mechanism for inturning the edge portion of a fabric to form a hem pocket, and means for guiding an endless elastic tape through the folder and into the formed hem pocket, said means including guiding devices located in advance of the folder, guiding devices located in rear of the stitching mechanism, and a guiding shield carried by the work support over which guiding devices and shield the elastic tape is stretched and directed into the hem pocket and to the stitching mechanism.

In testimony whereof I affix my signature.
HARRY E. DYKEMAN.
